UNITED STATES PATENT OFFICE.

FREDERICK W. ANDREW, OF GLEN HEAD, NEW YORK, ASSIGNOR TO EISEMANN MAGNETO CORPORATION, OF BROOKLYN, NEW YORK, A CORPORATION OF NEW YORK.

MAGNETO.

Application filed October 11, 1923. Serial No. 667,950.

To all whom it may concern:

Be it known, that I, FREDERICK W. ANDREW, a citizen of the United States, and a resident of Glen Head, Long Island, county of Nassau, and State of New York, have invented certain new and useful Improvements in Magnetos, of which the following is a specification.

My invention relates to magnetos and its object is to provide certain novel features for improving the construction and operation of such machines.

According to one feature of my invention, my new magneto is provided with a novel construction and arrangement of armature pole shoes and field magnet pole pieces, whereby the magneto operates at very low speeds to produce the necessary voltage. This is particularly advantageous in ignition magnetos for starting the engine.

Other features of my invention relate to an improved armature structure, a circuit breaker, and a short-circuiting device, as will be explained later on.

My invention finds special application in magnetos of the so-called flywheel type, although it is obviously not limited thereto.

The objects and advantages of my invention will be understood from a detailed description of the accompanying drawings, which show a practical embodiment as actually constructed and operated. In these drawings—

Fig. 1 is a face view of a flywheel magneto embodying the features of my invention, a portion of the field magnet casing being broken away to show the parts within;

Fig. 2 is a side view of the magneto partly in section, showing the same mounted on one end of a crank-shaft;

Fig. 3 is a transverse section, approximately on line 3—3 of Fig. 1, on an enlarged scale;

Fig. 4 is a fragmentary diagrammatic view showing one of the armature pole shoes spanning the air gap of the field magnet;

Fig. 5 is a view similar to Fig. 4, showing the approximate position of the field magnet relatively to the armature pole shoes at the moment of sparking;

Fig. 6 is a cross-section on line 6—6 of

Fig. 1, on an enlarged scale, showing the short-circuiting contact spring on the handle;

Fig. 7 is a fragmentary view showing the split hub on the armature disk for clamping the same on a suitable support;

Fig. 8 is an enlarged fragmentary view on line 8—8 of Fig. 1, showing the cam which operates the circuit breaker; and

Fig. 9 is a transverse cross-section on line 9—9 of Fig. 6, showing the recessed form of the handle on the armature disk.

The outer framework of the magneto shown in the drawings consists of a stationary disk or plate A and a rotary cylindrical casing B. Member A is the armature disk, and B constitutes the field frame. As shown in Fig. 2, one side of casing B is closed by a wall 1, while the other side is open, as indicated at 2. When the parts are assembled, the disk A fits into the opening 2, so that the members A and B provide a substantially closed outer casing. These parts are formed of a suitable non-magnetic material, such as aluminum, and are preferably cast each in one piece.

On the inside of casing B is mounted a ring-shaped permanent magnet M, which preferably fits snugly against the peripheral wall of the casing. The magnet M terminates at the points 3 and 4. To the polar ends of the magnet are attached pole pieces 5 and 6, which are preferably of soft iron. These pole pieces may be held in contact with the body of the magnet by any suitable means. In Fig. 1, screws 7 pass from the outside of casing B through the magnet into the pole pieces. The pole pieces 5 and 6 extend toward each other beyond polar ends 3 and 4 of the magnet M and are separated by an air gap a , which is considerably shorter than the distance between the polar ends 3 and 4. In the particular machine illustrated in the drawings, the air gap a is about one-half the length of a pole 5 or 6, but this proportion is not essential.

On the plate or disk A is mounted an armature comprising a core 8, on which is mounted a coil 9, and a pair of pole shoes 10 and 11 projecting from the ends of the core. It will be understood that the parts

8, 10 and 11 are of suitable magnetic material. By this I mean material such as iron, which is readily susceptible to magnetic influence. The coil 9 may consist of a primary and a secondary winding, or it may be a single winding. I prefer to make the core 8 of a bundle of wires, the ends of which fit snugly into openings 12 in the pole shoes 10 and 11, as illustrated in Fig. 1. The coil 10 is machine-wound and, after it is slipped on the core, the pole shoes are attached. This provides a very simple and cheap construction of armature, easily made and assembled, and yet having high magnetic efficiency. The pole shoes 10 and 11 may be of solid iron or composed of laminae. The entire armature structure is rigidly mounted in proper position on the disk A by screws or rivets 13, which pass through the pole shoes, or in any other practical way.

Attention is called to the fact that the pole shoes 10 and 11 have substantially straight inner sides 14, which terminate in polar tips 15. The core space between the sides 14 of the pole shoes is of ample length to receive a coil with a sufficient number of turns to produce the required voltage in the operation of the machine. In magnetos of this type there is no room for a coil of large diameter, so the required number of turns must be obtained by increasing the length of the coil. Hence, the advantage of the armature construction above described. The position of the armature is such that the pole pieces 5 and 6 of the revolving magnet move in close proximity to the curved polar faces 16 of the pole shoes.

The relation and proportion of the cooperating parts on the field magnet and armature are such that the polar tips 15 are substantially spanned by either pole piece 5 or 6, and the air gap a between the pole pieces is substantially spanned by either pole shoe 10 or 11. This is clearly indicated in Fig. 4. As a result of this novel construction and arrangement, the flux of the field magnet is short-circuited through the pole shoe 10 when the parts are in the position illustrated in Fig. 4, and practically no magnetic lines of force pass through the coil. It is here assumed that the field magnet rotates counter-clockwise, as designated by the arrow x . The direction of rotation is, of course, immaterial. As the field magnet continues to rotate, the pole shoe 10 breaks the short-circuit of the air gap, and the pole piece 5 comes opposite the pole shoe 10. At the same time, the other pole piece 6 moves across the pole shoe 11, with the result that the flux is suddenly and completely shifted through the coil. Fig. 5 indicates approximately the relative position of the parts at the moment of maximum induction, at which point the circuit is interrupted by the circuit breaker. If the magneto is used for ig-

nition purposes, the coil will have a primary and secondary winding, and the resultant current will be of high voltage. If the magneto is used for lighting purposes, the generated current will have a low voltage. These operations are well understood by the skilled engineer.

A magneto constructed as above described, produces ignition within a wide range of speeds. In practice I demonstrated that such a magneto operates satisfactorily on an engine running as low as 50 and as high as 3000 revolutions per minute. The circuit breaker contacts should be opened at the moment when the volume and rapidity of change of the magnetic flux through the coil are substantially at a maximum. This point of break changes for different speeds. The position of the parts in Fig. 5 is, therefore, to be considered merely illustrative. In the particular machine shown in the drawings, I found that the moment of approximately greatest magnetic efficiency occurred when the trailing pole piece of the magnet overlapped the polar face of the nearest pole shoe to the extent of about $5/8$ ths of an inch, as indicated at m in Fig. 5. This point will naturally vary with variations in the relative proportions and dimensions of the magnetic pole pieces and armature pole shoes, but it can be readily determined in any particular design of machine by proper tests and trials, as any electrical engineer will understand.

On the armature disk A is mounted a small plate 17, which carries a circuit breaker indicated as a whole by R. The plate 17 is supported on a pair of studs 18 extending inwardly from the armature disk A. In order to provide rotary adjustment of plate 17 on disk A, the plate is formed with arcuate slots 19, through which pass screws 20 for tightening the plate in adjusted position. The purpose of thus adjusting the plate 17 is to determine the moment at which the circuit breaker is operated to open the circuit of the coil, so that this break shall occur at the moment of maximum induction in the coil as previously explained.

The circuit breaker R comprises a fixed contact 21 and a movable contact 22 pivoted on a pin 23 extending from plate 17. The contact 21 is mounted in a small block 24 of insulating material. I prefer to make this block of bakelite, canvas or other similar material, which is strong and at the same time moisture-proof and oil-proof. This avoids the use of fine and fragile insulating parts on one side of the contact. The insulating block 24 is fixed on plate 17 by small screws 25, or otherwise. The pivoted contact 22 is grounded to the metal plate 17, and is normally held against contact 21 by a coil spring 26 mounted on a stud 27 of plate 17. The spring 26 is preferably a flat helical spring so arranged that the free end 26'

thereof bears against the rear portion of the pivoted contact 22, as may be seen from Fig. 1.

The contacts of the circuit breaker are 5 opened by a cam 28 projecting from a hub 29 of the field magnet casing B. The hub 29 is formed with a flange 30 for receiving rivets 31, or other fastening devices, by means of which the hub is secured to the 10 casing. Whenever the cam 28 strikes the rear end of pivoted contact 22, the contacts are interrupted. As pointed out, this break should take place substantially at the moment when the armature coil 9 is subjected 15 to the greatest magnetic influence.

The stationary armature disk A is so mounted that it can be readily adjusted in order to advance or retard the time of firing of the engine. For this purpose the disk 20 is provided with a handle 32, which is secured to the disk by rivets 33, or otherwise. After the armature disk has been moved to the desired position, it is clamped tight against accidental movement. This may be 25 accomplished in any practical way. In the drawings I have shown the disk A formed with a split hub 34 adapted to fit over a boss 35 on the crank case 36. Broadly speaking, the boss 35 may be regarded as 30 a support on which the armature disk may be radially adjusted and held in fixed position. The split hub 34 is provided with a screw 37, by means of which the connection between the armature disk and supporting 35 boss 35 may be loosened and tightened as desired.

In the preferred form of my invention, the handle 32 also constitutes part of a short-circuiting device, by which I mean a device 40 for short-circuiting the circuit breaker when it is desired to put the magneto out of commission, as for stopping the engine. The handle 32 is preferably curved at the sides to provide a shallow recess at one face thereof, as indicated at 32' in Fig. 9. At the base of the handle are fixed two insulating blocks 38 and 39, which are held in place by rivets 40, or other fastening means. Between the insulating pieces 38 and 39 is 50 clamped one end of a spring 41, which is preferably in the form of a flat strip of phosphor bronze, or other suitable material. The insulated spring 41 is electrically connected by a conductor 42 (shown in part in 55 Fig. 6) to the insulated contact 21 of the circuit breaker. The free end 43 of spring 41 is preferably bent toward the handle as shown in Figs. 6 and 9, so that only a slight movement of the spring is necessary to bring 60 it into contact with the handle. Since the spring 41 extends along the dished or recessed side of the handle and is practically flush with the sides thereof, the mere grasping of the handle by the fingers will not press 65 the spring into short-circuiting position. In

other words, the spring 41 is not in the way of using the handle for adjusting the rotary position of the armature disk A. At the same time, the spring 41 is easily accessible to short-circuit the circuit breaker by 70 simply pressing lightly against the spring, whereby the curved free end 43 is brought into contact with the metal handle 32.

In practice the magneto may be mounted in any suitable position relatively to the 75 engine. In Fig. 2, I have shown the magneto supported on the crank case 36 in such position that the rotary field frame is mounted directly on the projecting end 44 of the crank shaft 45, which passes through 80 the boss or bearing hub 35. The field frame B is locked on the engine shaft in any convenient way. In Fig. 2 there is a nut 46 engaging the screw-threaded portion 47 of the crank shaft and having a flange 48 arranged to overlie the outer wall of the casing. In a particular instance illustrated in the drawings, the flange 48 engages a disk 49 secured to the wall 1 of the casing by the 85 screws 50, or other otherwise. The disk 49 is dished or recessed so as to provide a pulley space 51 for receiving a rope or other flexible connection, by means of which the field magnet may be rotated by hand, as in starting 90 the engine. 95

Although I have herein shown and described an ignition magneto of a specific construction, I will have it understood that I have done so merely to explain a preferred embodiment of my invention and not by 100 way of limitation or restriction.

I claim as my invention:

1. In a magneto, a ring-shaped permanent magnet having its polar ends separated, arc-shaped pole pieces mounted in contact with the polar ends of said magnet, said pole pieces being arranged to extend toward each other beyond the polar ends of said magnet, a magnetic core provided at its ends with a pair of magnetic pole shoes having substantially straight inner sides and curved polar faces, the polar faces of said pole shoes and the pole pieces of said magnet being shaped and arranged to rotate in close proximity relatively to each other, the distance between the inner sides of said pole shoes being substantially spanned by either pole piece of the magnet, the polar faces of said pole shoes having each a length substantially equal to the air gap between said pole pieces, 110 and a coil mounted on said core between the inner sides of said pole shoes. 115

2. In a magneto, a rotary support, a ring-shaped permanent magnet carried by said support, arc-shaped pole pieces mounted in contact with the polar ends of said magnet on the inner face thereof, said pole pieces being arranged to extend toward each other beyond the polar ends of said magnet, a 120 stationary support, a magnetic core on said 125

stationary support, said core being provided at its ends with a pair of magnetic pole shoes having substantially straight inner sides and curved polar faces, the pole pieces of said magnet being arranged to move in close proximity to the polar faces of said pole shoes, the distance between the inner sides of said pole shoes being substantially

spanned by either pole piece of the magnet, the polar faces of said pole shoes having each a length substantially equal to the air gap between said pole pieces, and a coil mounted on said core between the inner sides of said pole shoes.

FREDERICK W. ANDREW.
